ROPE TWISTING AND LAYING MACHINE

Anton Kraft, Olpe, Germany

Application September 6, 1940, Serial No. 355,659
In Germany December 4, 1939

3 Claims. (Cl. 57—58)

Rope twisting machines are known, which are equipped with a winding spool for the ready rope and with a frame circulating around said spool. The material for twisting is conducted along the circulating frame in being submitted to back turning. An arrangement is made, to pull into the machine the finished rope from a separate pulling-in disc. With this object in view, the pulling-in disc coupled with the machine drive is mounted in a body in the circulating frame, 10 said body remaining in the position of rest, the rope being wound several times around this pulling-in disc. From this pulling-in disc the rope is wound by means of a laying mechanism upon the winding spool also coupled with the machine 15 drive.

Machines of this type are of rather complicated construction and relatively long. The longer the circulating frame is, the greater become the resistances and checkings preventing a rapid speed of the machine. As further during the service the number of the rope turns wound around the winding spool and therewith the diameter of the wound body become continually greater, the length of the product wound on 20 changes at every rotation of the winding spool. Consequently strong pulls and tensile stresses are produced in the finished product between the pulling-in disc and the winding spool. This causes, however, when fine and soft material is 25 worked, for instance strands, prejudicial alteration in cross section owing to the stretching of the rope material.

For this reason the revolving speed of the winding spool must be continually supervised and from time to time adapted to the other existing conditions, this being rather difficult. As a rule, this is effected by corresponding adjusting of a slipping clutch of the drive for balancing at least partly the differences which occur in the machine 30 between the introducing of the rope and the pulling out of the same.

These inconveniences are done away with on the one hand by the free pulling-in of the material directly by the winding spool itself, which 35 means with omission of any intermediate element, on the travel from the machine axis to the winding spool, whereas on the other hand a direct dependency between the drive of the winding spool and the pulling into the machine is obtained thereby that the unwinding of the finished rope always corresponds accurately to the pulling-in, so that the diameter of the wound material on the spool is no longer of importance.

According to the invention, this is attained in 40

that the rope is pulled by the winding spool directly into the machine, which with this object in view is driven by an endless belt circulating with uniform speed and wound under spring tension around the wound up rope material on a portion of the circumference of the spool. One of the two guide rollers for the endless belt is mounted on a sliding body shiftable relative to the body in the framework, said sliding body being shifted under the action of a spring for pressing the endless belt against the wound rope. The sliding body is equipped with racks, in which mesh toothed wheels on a shaft journaled in the body in the frame, the tension spring being helically wound on said shaft and fixed so that it brakes the turning movement of the shaft.

Besides a simpler construction and much lower cost of production, a circulating speed increased in comparison with that of the known machines and thereby a considerably increased efficiency are obtained.

An embodiment of the invention is illustrated by way of example in the accompanying drawings in which

Fig. 1 shows the body in the frame in elevation and

Fig. 2 in top plan view.

Fig. 3 is a horizontal section through the sliding body on line III—III of Fig. 1.

Fig. 4 is a vertical section on line IV—IV of Fig. 1 and

Fig. 5 a vertical section on line V—V of Fig. 1, the endless belt being removed, and

Fig. 6 a similar section as Fig. 4 being viewed from the outer side.

In the floor stands 1 and 2 of the machine frame a circulating frame revolves which consists of transverse elements 3 and 4 and connecting tubes 5. The transverse element 3 has on its outer side a hollow shaft 3a and on its inner side an extension 3b, on which the body 6 is suspended. The transverse element 4 has on its outer side a shaft journal 4a and on its inner side a hollow pin 4b for the suspension of the body 6. On the outwardly directed free end of the shaft 4a a pulley 7 for a wedge-shaped belt is keyed, which is coupled with the source of power and is destined to operate the machine, whereas on the inwardly directed free end a driving worm 9 is keyed, which is coupled with a worm wheel 8 on the body 6 and destined to drive the mechanism for the winding and laying of the ready product. On the outwardly directed side of the floor stand 1 a stationary separating plate 10 is mounted centrically to the shaft 3a,

the wires 11 and 12 of the material to be twisted being introduced by means of this separating plate 10. In the circulating frame the body 6 is suspended in the stable equilibrium position on the pins 3b and 4b of the transverse elements 3 and 4, said body remaining in the position of rest during service. With this object in view the transversely extending portions 6a of the body 6 are suspended on the screws 15 which connect the two halves 13 and 13a of the bearing. The bearing halves 13 and 13a transmit the load of the body to the pins 3b and 4b. Change wheels serve to drive the mechanism arranged on the body and destined for winding and laying the finished product. The ratio of transmission of these changing wheels is adapted from case to case to the existing decisive conditions, such as thickness of the material and length of turn. On the outer end of the transverse shaft 16 driven by the worm wheel 8, the toothed wheel 17 is keyed which meshes with the wheel 18 on the transverse shaft 19. On the inner end of this transverse shaft 19 a toothed wheel 20 is keyed which meshes with a toothed wheel 21 on a transverse shaft 22. Inside the body 6 a driving roller 23 is keyed on shaft 22, said roller destined to drive an endless belt 24 circulating in the direction of the longitudinal axis of the machine. This endless belt 24 is conducted over rollers 25 and 26 arranged the one above the other, the lower roller 25 being mounted on the body 6 and the upper roller 26 on a sliding body 42 on the body 6. During its circulation in the lower range of the winding spool 28 around which the finished rope has to be wound the endless belt is pressed against the wound up material. The winding spool 28 removably mounted on the transverse shaft 29 is thus rotated. This spool 28 in turn drives the mechanism for the actuation of the laying nut 30a moving to and fro on the screw threaded spindle 30 and effecting the laying of the rope or strand on the spool 28. This is attained in that the toothed wheel 33 meshing with the toothed wheel 31 on shaft 32 rotates together with the spool 28. A second toothed wheel 34 is keyed on shaft 32 and coupled with the toothed wheel 35 mounted on the screw threaded spindle 30.

The stationarily mounted lower roller 25 of the transverse shaft 40 (Fig. 5) of the body rotates in bracket-like oblique arms 41 of the left hand transverse part 6a of the body 6. As, during the service, the diameter of the wound body increases with increasing winding on the spool 28 and consequently the tension in the endless belt 24 increases, an equalisation for this excessive tension is produced by the special means of mounting of the upper roller 26. This roller 26 is journalled in a slideable body 42 controlled by spring and shiftable in guide grooves in the cheeks of the body 6. The slideable body 42 has racks 42a (Figs. 3 and 5) on both outer ends, these racks meshing with toothed wheels 43 on the transverse shaft 44 journalled in the body 6. In the middle of shaft 44 a spiral spring 45 is fixed which is wound around the shaft and extends towards both sides of this shaft, the free ends of this spiral spring 45 being fixed on the body 6 so that the toothed wheels 43 have the tendency to shift upward the slideable body 42 by the action of this spring. In the form of construction illustrated, the free ends of the spiral spring 45 terminate each in an eye 45a, these eyes being hooked on a transverse rod 46 fixed on the body 6 above the shaft 44. When the

5 diameter of the wound body on spool 28 increases, the slideable body 42 is moved more and more downwards, owing to the increased tension of the endless band 24, in overcoming the oppositely directed tension of the spring 45, so that the endless band 24 can adapt itself automatically to the actual thickness of the wound body on spool 28.

10 To make it possible that the circulating frame can be selectively turned in the one or other direction of rotation, a second driving worm 8a (Fig. 2) with screw-threads directed oppositely to the worm wheel 8 may be mounted on the transverse shaft 16.

15 A guide roller 37 is arranged at one end of a holder 36 in a slot 14 (Fig. 4) of the hubs of the transverses 3 and 4, and on the other end a guide roller 38 from which the rope or strand 27 is conducted through one of the connecting tubes 5 and then on the side of the transverse 20 4 over guide rollers 38, 37 deflected again into the direction of the axis of the machine. After having come out of the hollow pin 4b the ready product 27 is conducted to the spool 28 after having passed between the upright guide 25 pins 30b of the shifting nut 30a, so that the product is wound up. In this kind of guiding of the twisted material along the circulating frame this material is twisted with two twistings for each rotation of the circulating frame.

30 The operation is as follows:

35 The individual wires 11, 12 (Fig. 1) pass through holes in the stationary separating plate 10 into the hollow shaft 3a of the machine and deflected again from the axis of the machine over the roller 37, the two rollers 38 and again over the roller 31 of the transverse 4. To the wires 11, 12 the first twisting is imparted behind the separating plate 10 and prior to the introduction into the machine. A second twisting in the same direction takes place in front of the worm 8 when the twisted wires come out of the hollow pin 4b. From here the finished rope or strand 27 is fed directly between the guide pins 30b of the displacing nut 30a to the winding spool 28. This winding spool is driven by the endless band 24. Instead of this endless band an endless belt of leather straps of wedge-shaped cross-section may be used. By means of exchangeable toothed wheels 17, 19, 20, and 21 (Fig. 2) which are selected in accordance with the existing conditions, the drive of the endless band 24 is coupled with the machine drive, so that a continual accurate equalisation of the length of the winding on to the spool 28 and of the drawing of the twisted material into the machine takes place. As further the laying mechanism of the reciprocating travelling nut 30a is coupled with the spool 28 by change wheels 33, 32, 34, and 35 (Fig. 2) also adapted to the actual conditions, the windings of the product are laid accurately the one at the side of the other without any overlapping or other irregularities. When the diameter of the wound body on spool 28 increases, an equalisation of the tension of the endless band 24 by corresponding lowering of the slideable body 42 controlled by spring takes place.

70 Instead of the twisting machine shown by way of example, in which the material is twisted partly in front of the machine and partly when passing through the same, other twisting machines may be equipped with the elements according to the invention in which the twisted material is forced to carry out back twistings,

as is absolutely necessary, for instance, at the twisting of hard wire material. Twisting machines may also be equipped with the elements according to the invention in which machines uniformly directed twistings are brought into the bundle of wires when passing through the machine, these twistings being continually used in the opposite twisting direction for beating the wire rope or strand on a press cheek.

I claim:

1. A twisting machine with a spool for winding up the finished rope, comprising in combination a circulating frame in which the rope is conducted for back twisting, a winding spool pulling the rope directly into the machine, an endless belt driven at uniform speed and driving said winding spool, and springs for pressing said end-

less belt against a portion of the circumference of the rope wound on said winding spool.

2. Machine as specified in claim 1, comprising in combination with the endless belt, guide rollers for this endless belt, a shiftable sliding body mounted in said circulating frame, and a spring adapted to shift said sliding body so that it presses the endless belt against the wound rope.

3. Machine as specified in claim 1, comprising a shiftable sliding body, racks on the ends of said sliding body, a shaft in the body in the circulating frame, toothed wheels on said shaft meshing with said racks, and a clamping spring helically wound on said shaft and fixed so that it brakes the rotary movement of said shaft.

ANTON KRAFT.
